UNITED STATES PATENT OFFICE.

GEORGE A. LONG, OF HARTFORD, CONNECTICUT.

SPARK-PLUG.

1,114,157.

Specification of Letters Patent. Patented Oct. 20, 1914.

Application filed January 2, 1914. Serial No. 809,908.

To all whom it may concern:

Be it known that I, GEORGE A. LONG, a citizen of the United States, residing at Hartford, in the county of Hartford and 5 State of Connecticut, have invented certain new and useful Improvements in Spark-Plugs, of which the following is a specification.

This invention relates to spark-plugs, the 10 object of the invention being to provide an article of this character which is simple in construction, effective in action and which is longer-lived than those now in general use but which is practically no more expensive.

15 In the drawings accompanying and forming part of the present specification I have shown in detail one of the several convenient forms of embodiment of the invention which to enable those skilled in the art to practice 20 the same will be set forth fully in the following description. I do not restrict myself to this showing; I may depart therefrom in several respects within the scope of the invention defined by the claims following said 25 description.

Referring to said drawings: Figure 1 is a side elevation of a spark-plug involving my invention. Fig. 2 is a longitudinal central 30 sectional view of the same. Fig. 3 is a bottom plan view of the plug, and, Fig. 4 is a transverse section on the line 4—4 of Fig. 2 looking in the direction of the arrow.

Like characters refer to like parts throughout the several views.

35 A spark-plug embodying my invention comprises conductors insulated from each other, and arranged in sets, the conductors of the respective sets being separated to provide spark gaps in conjunction with means 40 whereby current can be directed through any one set of conductors. I do not restrict myself to any particular construction, although ordinarily I prefer that the spark-plug comprise a body member and an insulating member set therein, the insulating member being provided with a group of conductors, while the body member has a corresponding number of conductors coöperative 45 respectively with those on the insulating member. In combination with the several conductors is provided switch means and means whereby the switch means can be put into electrical connection ordinarily at will with any desired conductor on the insulating 50 member. A plug such as the foregoing can be used in any connection where those of ordinary kind are now used.

With the foregoing general observations I will refer more in detail to the showing made by the annexed drawings. The body 60 member is denoted by 2 consisting as shown of a shell to receive the insulating member 3, the lower end of which as illustrated extends short of the corresponding end of the body member, while the upper end of which extends through and beyond the upper open 65 end of the body member which as represented has fitted into it a nut 4 to clamp the insulating member 3 in place. The body member may as illustrated be provided with 70 external threads 5 to mount it in place and may have the polygonal portion 6 to facilitate such mounting. The foregoing is a brief description of the body member and insulating member of a familiar type of 75 plug. Any other equivalent parts might be substituted therefor, the invention not concerning these or like details but residing rather in certain broad relations as already intimated, and as will be more clearly expressed in my claims.

The conductors to which I have alluded may be of any desirable character and number. The body is shown as equipped with three of such conductors each denoted by 7 85 and consisting of a rod extending entirely through and beyond the lower end of the insulating member 3, the upper ends of the conductors or rods 7 having semi-spherical 90 heads 8, the purpose of which will be herein-after explained. The body 2 is furnished with a corresponding number of conductors 9 of approximately L-shape, the shanks of the conductors being fitted in bores in the lower edge of the metal body 2, while their 95 branches are bent toward the lower projecting ends of the complementary conductors 7. Each conductor 7 is separated from its companion conductor 9 by a gap. The conductors thus far described are in themselves 100 not new, although I believe it is new with me to arrange longitudinally extending conductors as 7 eccentrically of an insulating member.

The conductors 7 are adapted to be connected in desired order with a source of electrical energy such as a battery in any desired manner, manually operable switching means being shown for the purpose. The upper portion of the insulating member 3 is shown molded around the lower portion of the stud or screw 10, and around the projecting portion of the screw is fitted the conducting sleeve 11 which as shown rests on

the top of the insulating member 4. It should be stated that this insulating member can be made of porcelain or any of the compositions now ordinarily utilized for making such parts. Surrounding the metallic sleeve 11 is the collar 12 of insulating material such as fiber, this collar being rotatable on the sleeve 11 which acts as a suitable pivot for the collar. The collar 12 as shown 10 is counterbored in its under side as at 13 to receive the top portion of the insulating member 3. The sleeve 11 is furnished with an outwardly extending head 14 in the form of an annular flange which overlies the collar 12 and which acts to clamp the collar 12 in place, the sleeve in turn being clamped in place by the nut 15 threaded onto the upper end of the stud or screw 10. Around this stud or screw 10 may be coiled the bared 20 portion of a lead wire which can be clamped solidly in place and in electrical connection with the sleeve 11 or its head 14 by the nut 15. Opening into the upper surface of the collar 12 and into the counterbore 13 is a 25 bore 16 which receives in it the cylindrical plug members 17 and 18 between which is interposed the coiled spring 19 which tends constantly to separate the two plug members 17 and 18. These plug members with the 30 intermediate protractile spring present a switch device for electrically connecting the sleeve 11 or equivalent parts with a desired conductor 7 on the rotation of the collar 12. As shown the 35 lower plug member 17 has a cavity 20 to receive in alternation the semi-spherical heads 8 at the upper ends of the rods 7 to thus prevent accidental movement of the collar and therefore breaking of the circuit when a 40 plug member is in electrical contact with a conductor as 7. In Fig. 2 the cavity 20 is shown as receiving the head 8 of a conductor 7 or that conductor at the left in said view, by virtue of which if there be a lead wire 45 connected with the stud or post 10 the current will flow from the wire to the post, sleeve 11, plug member 8, spring 16, plug member 17, the conductor 7 in question, the coöperating conductor 9 and body member 50 2 to ground. By turning the collar 12 the plug member 17 can be put into electrical connection with another of the conductors 7.

As already observed the present plug is capable of use in many connections; although 55 it is of particular utility when used on the engine of an automobile. It frequently happens that one burns out a spark plug on the road, and in this event has to run his car on less than all the cylinders. By cutting out 60 terminals that may have become useless from any cause, such as breaking of the insulating member 3 or a collection of refuse in a spark gap, a fresh set of terminals may be cut in

and the plug made to act. As noted I can depart radically from the construction shown 65 and hereinbefore fully described, this being merely one of many different ways of carrying my invention into effect.

What I claim is;

1. A spark plug comprising a body, an insulating member supported in said body and provided with several conductors, and a movable insulating member directly supported by the first mentioned insulating member and provided with switch means 75 for successively engaging the conductors on the movement of said movable insulating member.

2. A spark plug comprising a body, an insulating member in said body, provided with 80 several conductors, a second insulating member supported by the first insulating member and provided with switch means, the two insulating members being connected for relative movement to cause the switch means to 85 successively engage said conductors on said relative movement.

3. A spark-plug comprising a body, an insulating member in said body provided with 90 a number of conductors, a rotary member on the insulating member, and switch means for successively engaging the conductors on the insulating body on the turning of said rotary member.

4. A spark-plug comprising a body, an insulating member in said body provided with 95 a number of conductors, a rotary insulating part on said insulating body provided with switch-means for successively engaging the conductors on the body on the turning of 100 said rotary part, and an electrical conducting device in constant electrical connection with said switch-means.

5. A spark-plug comprising a body, an insulating member in said body, provided with 105 a number of conductors, an insulating member supported for rotation by said other insulating member and having switch-means to successively engage the conductors on the body on the turning of said rotary insulating member, a stud connected with and extending from the first mentioned insulating member, a sleeve surrounding the stud and inclosed by the rotary insulating member, said sleeve being of conducting material and 110 having a flange overlying and constantly engaging said switch-means, and a nut threaded onto the stud, the nut being adapted to bind a lead wire against said flange.

In testimony whereof I affix my signature in presence of two witnesses.

GEORGE A. LONG.
